UNITED STATES PATENT OFFICE.

ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN.

TOOL-RETAINING DEVICE.

Application filed May 11, 1925. Serial No. 29,644.

This invention relates generally to pneumatic hammers and the like and has particular reference to means employed for retaining the rivet set or other tool.

- 5 In the operation of pneumatic tools, as the hammer is withdrawn from contact with the work, the impulses on the tool are liable to drive the latter out of the body of the hammer. This is, of course, undesirable. 10 However, when it is desirable to remove the tool the same should be readily removed without any difficulty.

The object of this invention is to provide a retainer for a rivet set or like tool, which 15 serves to prevent the accidental discharge of the tool from the hammer as the latter is withdrawn from the work; which has a resilient mounting to cushion the blows on the tool when the hammer is operated out of contact with the work; and which is readily displaced from its effective retaining position to permit the operator to remove the tool.

Still other and ancillary objects of the 20 invention will be apparent from the description of the exemplary embodiment of the invention as illustrated in the accompanying drawings, in which

Figure 1 is a cross sectional view of the 25 nose of a pneumatic hammer equipped with the retaining device.

Fig. 2 is a side view in elevation of the 30 device shown in Fig. 1 with the device laterally offset to permit removal of the tool.

Fig. 3 is a cross section taken on the line 35 3—3 of Fig. 1.

Fig. 4 is a view in perspective of the retaining clip.

It will be understood that the particular 40 embodiment of the invention shown in the accompanying drawings is given by way of illustration and explanation of the nature of the invention and that it is not to be construed as a limitation thereof to the precise construction illustrated. It is further to be understood that such other embodiments, 45 constructions and alternative forms are contemplated by the present invention as will fall within the scope of the appended claims.

50 In the drawings, 10 represents the barrel of a pneumatic hammer having an internally fixed guide sleeve 11 closing the bore 12 at the nose or forward end of the barrel. Within the cylindrical bore 12 of the barrel a piston (not shown) is reciprocal. The guide

sleeve 11 is suitably shaped internally to receive a rivet set or other tool generally indicated by the numeral 13. In the present instance the end of the tool 13 when inserted in the sleeve is cylindrical in the forward end of the sleeve 11 and hexagonal toward the rear, the rear end of the tool projecting beyond the sleeve 11 for receiving a blow from the piston. A suitable enlarged portion 14 is provided on the tool 60 preferably as an annular rib or flange about the tool near the end of the sleeve 11. A projecting portion is also formed on the nose of the barrel 10 preferably as an annular flange or rib which may be removable, and 65 in the present instance is constituted by a split ring 15 set into a suitable channeled recess therefor in the barrel 10. The retaining device in the present instance comprises a clip mounted on the nose of the hammer, 70 which clip has fingers underlying the rib 14 to engage the same by cooperation therewith. In the present instance the fingers are provided by a U-shaped band 16, being 75 so shaped to permit removal laterally away from the tool 13 which is normally encompassed by the U. The U-band 16 is made integral with suitable side supporting means at right angles therewith extending longitudinally of the hammer in the form of strips 80 85 17 in the present instance, being spaced apart to lie on opposite sides of the nose. The rear ends of the side strips 17 have arcuate-edged flat flanges 18 extending inwardly toward the sides of the barrel 10 and adapted to 90 register circumferentially therewith, the two flanges preferably lying in the same plane. A heavy coiled spring 19 is interposed between the arcuate-edged flanges 18 and split ring 15 on the barrel. The spring 19 has a 95 diameter such that it loosely encompasses the barrel 10 and such that it will lie between the opposite side strips 17 of the retaining clip. The upper coil or turn 20 is preferably ground to present a flat seat 21 for the 100 two arcuate flanges 18. Likewise the lower coil or turn 22 of the spring 19 is ground to form a flat seat 23 upon the ring 15.

The effect of the spring 19 is to move the retainer rearwardly of the hammer, but it is 105 desirable to have the active retaining fingers or band 16 disposed forward of the end of the hammer so as to permit of some motion of the tool without engaging the retaining fingers. In order to position the retaining clip for this 110

purpose the spring 19 is kept under slight compression in the normal relation shown in Fig. 1, and stop means is provided between the clip and the barrel to position the clip by limiting rearward motion under influence of the spring. This is accomplished by providing an abutting engagement between the retainer clip and the barrel 10. In the present instance this is accomplished by having the 10 forward portions of the side strips 17 offset inwardly of the clip providing stop shoulders 24 in the side strips 17 which shoulders engage the forward end of the barrel 10 as indicated at 25.

15 The provision of this type of retaining clip and the mounting means therefor makes the same particularly advantageous. The spring 19 having the two end turns forming parallel seats 21 and 23 in the normal position of the device as shown in Fig. 1, keeps the retaining sides 17 normally parallel with the tool. Hence, the fingers 16 are properly positioned to engage the rivet set flange 14. When the tool is held free from the work and operated, 20 as in withdrawal, the impulse of the hammer drives the tool forward and the flange and fingers engage moving the clip forwardly with the tool, the clip cushioning the blow against the spring 19. In order to remove the 25 tool the retaining clip may be forced laterally with a swinging motion relative to the barrel thus compressing the spring on one side only as shown in Fig. 2. This lateral swinging movement is sufficient to bring the U-band 16 out of engaging position with the flange 14 on the tool, thus permitting the latter to be 30 removed from the sleeve 11. In Fig. 2 the flange 14 is shown below the top edge of the band 16. Not only the spring 19 but also 35 the resiliency of the clip itself normally holds it parallel with the hammer barrel. This is, of course, due to the engaging of the barrel sides by the arcuate edges of the flanges 18. The retaining clip thus need not be removed 40 from the hammer to effect removal of the tool and no part of the retaining device need be loosened or unclamped.

45 On the other hand, the retaining clip may be easily removed from the barrel when desired. Because of its particular shape as shown in Fig. 4, it is readily made of stamped sheet metal and may be provided for the tool as a renewable part.

50 It will thus be seen that by the above construction I have provided a thoroughly practical retaining device for tools in pneumatic hammers and the like comprising an inexpensive retaining clip and a simple mounting means therefor, and further a device which 55 is readily operable for removal from the tool without removing or demounting any part of the device.

I claim as my invention:

1. A tool retaining device for pneumatic

hammers and the like comprising, in combination with the hammer and the tool, an annular rib at the forward end of the hammer, a flange on the rivet set or tool adjacent the end of the hammer, a U-shaped retaining member forward of said tool flange embracing the tool and adapted to engage with the flange, supporting strips for said retaining member on opposite sides of the hammer, said strips having a portion thereof abutting the end of the hammer and another portion thereof lying alongside the barrel of the hammer, flat arcuate-edged flanges on said strips extending inwardly toward the hammer, and a coiled spring compressed between said flanges and the rib of the hammer within the side strips.

2. A tool retaining device for pneumatic hammers and the like comprising, in combination with the hammer and the tool, a coiled spring about the barrel of the hammer, a unitary member mounted on said hammer for rearward motion with respect thereto by said spring, said member having two opposite sides lying alongside the hammer and having portions adapted to limit the rearward motion of the member with respect to the hammer by engagement therewith, said sides being joined by a U-shaped portion, said unitary member having parts thereon to engage the tool in the forward motion thereof, and said sides having arcuate-edged flanges encompassing the hammer and engaging with the coiled spring to effect the rearward motion of the unitary member against the limiting portions thereof.

3. A tool retaining clip for pneumatic hammers and the like comprising, in combination, a U-shaped portion adapted to embrace the tool, two opposite side strips extending at right angles to said portion from the sides of the U, and inwardly extending flanges at the ends of said side strips, said flanges being substantially parallel with the U-shaped member and having elongated arcuate edges to engage with the sides of the hammer barrel to resist displacement of the clip from said hammer.

4. A retaining clip for pneumatic hammers and the like comprising a U-shaped member of somewhat resilient material having two arms extending alongside of the barrel of the hammer, the base of the U-shaped member being itself U-shaped at right angles to the main U for provision of a tool receiving recess therein, arcuate surfaces at the free ends of the arms extending substantially parallel to the base arranged normally to be resiliently pressed against opposite sides of the barrel, said arcuate surfaces being of a length to encompass the major portion of the circumference of the barrel so that lateral motion of the clip with respect to the barrel about the encompassing surfaces as a pivot causes separation.

ration of the arms of the **U** against the resiliency of the member to permit removal of the clip from said hammer.

5. A device of the character described having, in combination with a power hammer and a tool positioned thereon, a tool retaining clip formed from a single piece of sheet metal having a part adapted to embrace said tool

and having a pair of parts resiliently engaging diametrically opposed arcuate portions 10 of said hammer yieldingly to maintain said clip on said hammer.

In testimony whereof, I have hereunto affixed my signature.

ERNEST H. SHAFF.
